US00D689864S

(12) **United States Design Patent**
Vaughan et al.

(10) **Patent No.:** **US D689,864 S**
(45) **Date of Patent:** **** Sep. 17, 2013**

(54) **MOBILE DEVICE PHOTO SCANNER**

(75) Inventors: **Corey R. Vaughan**, Providence, RI (US); **Jason E. Durant**, Warwick, RI (US)

(73) Assignee: **inMusic Brands, Inc.**, Cumberland, RI (US)

(**) Term: **14 Years**

(21) Appl. No.: **29/413,388**

(22) Filed: **Feb. 15, 2012**

(51) LOC (9) Cl. **14-02**

(52) U.S. Cl.

USPC **D14/421**
